UNITED STATES PATENT OFFICE.

AUGUST RIEBE, OF BERLIN, GERMANY, ASSIGNOR TO THE FIRM OF DEUTSCHE WAFFEN- & MUNITIONSFABRIKEN, OF BERLIN, GERMANY.

SHAFT-BEARING.

SPECIFICATION forming part of Letters Patent No. 687,406, dated November 26, 1901.

Application filed April 17, 1900. Serial No. 13,244. (No model.)

To all whom it may concern:

Be it known that I, AUGUST RIEBE, mechanical engineer, a subject of the King of Prussia, German Emperor, residing at 15^d Zwingli-strasse, Berlin, Kingdom of Prussia, German Empire, have invented certain new and useful Improvements in Shaft-Bearings; and I do hereby declare the following to be a full, clear, and exact description of the invention, so such as will enable others skilled in the art to which it appertains to make and use the same.

This invention relates to an adjustable shaft-bearing especially suitable for employment as a ball-bearing, the peculiarity of which consists in the construction of the folding casing for inclosing a divided race-ring bush, the object being to enable the latter to be adjusted when free from the casing and to be subsequently rearranged to the exact shaft center, the closing contrivance, by means of which the two parts of the race-ring bush are held together, being temporarily unfastened for such adjustment.

In the accompanying drawings, Figure 1 is a transverse section, and Fig. 2 a longitudinal section on the line A B of Fig. 1, of a ball-bearing constructed according to the invention. Figs. 3 and 4 are respectively an end view and a side view of the same. Fig. 5 is an end view of the divided ball-bearing race-ring bush. Fig. 6 is a side view of the same.

a is the casing-base, the given position of which determines the position of the axis of the shaft.

The folding bearing-casing, which is capable of being arranged on an invariable central line in relation to the base a, consists of segmental parts or clamps p and q, the former of which parts, p, can turn on the hinge-bolt b in the base a, while the latter, q, is connected with the piece p by means of the hinge-joint r and terminates in a slotted shoe-shaped piece to receive the fixing-screw c and having a shoulder or bearing-piece s for the nuts to enable the piece p to be screwed up to the base a. The said screw c, which is firmly held by its prismatic head engaging in a hollow in the base a, passes through the slot in the shoe-shaped part of the piece q, so that

after the nuts have been loosened it can be shifted and placed out of the range of the piece q, which can then be turned upward. For the folded or closed position of the casing it is requisite that an extension of the piece p should rest against a stop k, Fig. 1, of the base a.

The ball-bearing bush, Figs. 5 and 6, to be inclosed in the casing p q consists of a casing-ring d, which receives the divided race-ring u v for the balls, the two halves of which casing-ring are joined together by means of a hinge e and detachably connected on the other side, where they overlap one another, by means of a pin f. The inclosure of the ball-bearing bush in front is effected by a disk n, which is provided as a means of adjustment and fits into a screw-thread in the two parts of the bush d, while it is also provided with a packing-ring surrounding the shaft w. A similar packing-ring is introduced at the back, whereby the lubricating material is prevented from running out of the interior of the bearing. The remainder of the ball-bearing arrangement itself is not essential to the present invention. It may be observed that for holding the two rows of balls in the form of the invention shown sheet-metal rings are inserted and that the running-surface is formed by means of a ring surrounding the shaft w. The adjustable ball-bearing bush thus arranged or a similarly-constructed bearing-piece is placed inside the casing, consisting of the segmental clamps p q. As in Sellers' bearing, the bearing has a certain mobility in consequence of the spherical formation of the bearing-surfaces, which fit one another, as will be seen at Fig. 2. The effective bearing-surfaces of the casing serving for the exact centering of the bearing are placed at positions in the segmental clamps p q lying opposite to one another and are discontinued at other parts.

The form of construction described enables the bearing to be adjusted and precisely rearranged in the following manner: The screw c is loosened and the casing formed by the segmental clamps p q turned back, so that the bush d is exposed on all sides. If the exposure extended only to a part of the circumference—as, for example, by the removal of

an ordinary bearing-cover—the object of a complete exposure of the bearing would not be attained. The part of the bearing held loosely on the shaft, which in the present 5 case is the ball-bearing bush *d*, can consequently be adjusted when in a perfectly free position, the right degree of adjustment being ascertainable by turning the bush with the hand. The adjustment of the ball-bearing shown is effected by the turning of the disk *n* after a detent *i*, Figs. 2 and 3, which 10 serves for keeping the bearing in the adjusted position, has been unscrewed. Further, the bush can be opened after the pin *f* 15 has been taken out for the purpose of examining or cleaning the interior. When the adjustment has been effected and the bush runs properly on the shaft *w*, the casing *p* *q* is folded down for the purpose of inclosing 20 it, the nuts of the screw *c* being screwed tightly against the shoulder *s* of the piece *q*, the two segmental clamps close on the bush *d* and shaft *w*, and the latter is forcibly adjusted to the exact axial center. By the resting 25 of the foot of the clamp *p* on the stop *k* the invariable centering position is attained, so that the center of the shaft is forced to take the original position. At the same time the temporary closing contrivance of the ball-bearing bush *d*, which consists of the pin *f*, 30 is released, so that the strain is taken up by the casing.

The feeding of the lubricating material to the bearing can be effected by means of a hole *o* in the bush *d*, in the interior of which 35 a spring-valve *z*, Fig. 1, is so arranged that it forms an automatic closing contrivance, preventing the lubricating material from running out. The hole *o* is accessible by means 40 of a corresponding hole *t* in the clamp *p*.

The folding arrangement of the interior

bush enables the bearing to be conveniently cleaned and the sliding surfaces and balls to be examined even when the space adjoining the shaft-bearing is limited. In the case of 45 the employment of a closed bush the rings would have to be pushed out sidewise, for which purpose more room would be requisite.

It is obvious that instead of the ball-bearing another inserted bearing-piece capable of 50 automatic adjustment can be placed inside the folding casing.

What I claim is—

1. The combination with a casing composed of sections hinged together, a base, a hinge-joint connecting one end of said casing with 55 said base, and a fixing-screw connecting the other end of said casing with said base, of a shaft-bearing having an adjustable bush separate from said casing, said bush being divided and arranged to open out in order that the bearing may be readily opened and examined.

2. The combination with a casing composed of sections hinged together, a base, a hinge-joint connecting one end of said casing with 65 said base, and a fixing-screw connecting the other end of said casing with said base, of a shaft-bearing having an adjustable bush separate from said casing, said bush being divided and arranged to open out in order that the bearing may be readily opened and examined, and a pin serving as a preliminary 70 closing contrivance for holding the parts of said bush during adjustment.

In witness whereof I have hereunto set my hand in presence of two witnesses.

AUGUST RIEBE.
